TOY ROUNABOUT

John Madaloni, Jamaica, N. Y.

Application September 22, 1952, Serial No. 310,749

3 Claims. (Cl. 272—31)

1

This invention relates to amusement devices and more particularly to an activated toy in the nature of a merry-go-round.

It is a primary object of the present invention to provide a toy of this kind with a revolving platform on which are mounted toy figures, with improved means for operating the platform which means is simple in construction, readily installed and replaced and easy to manipulate.

Another object of the invention is to provide a toy of this kind having a revolving platform with elastic means for rotating the platform, which means includes a novel device for mounting, demounting and energizing the elastic means.

A specific object of the invention is to provide a toy merry-go-round with a rubber band motor having bearing members for detachably supporting the ends of the rubber band, one of the bearing members serving as means for energizing the rubber band.

Yet another object of the invention is to provide a toy of this kind which is simple in construction and which can be manufactured at a reasonable cost.

For further comprehension of the invention and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a toy embodying one form of the invention.

Fig. 2 is a vertical sectional view taken on the plane of the line 2—2 of Fig. 1.

Fig. 3 is an enlarged top plan view of a fragment of the top plate of the toy.

Fig. 4 is an enlarged side elevational view of the elastic motor.

Fig. 5 is a similar view turned slightly.

Fig. 6 is a vertical sectional view taken through the elastic motor with its enclosing tube in position.

Fig. 7 is a perspective view of a modification of the invention.

In Figs. 1 to 6, inclusive, of the drawing, a toy made in accordance with the invention is shown, comprising a frame structure including a circular base plate 10 having a depending flange portion 11 for mounting the toy on a supporting surface. A trio of upright opposed posts 12 on the base plate support a flanged roof or top plate 13 at their upper ends. The base and top plates and the posts may be made of plastic or other suit-

2

able material, and the posts may be either tubular or solid.

The top plate 13 is formed with a central opening 14 having an enlarged portion 15 therearound. 5 The enlarged portion is formed with a roughened upper surface 17. A tubular member 18 is suspended from the top plate and has a flange portion 19 at its top end adjacent the bottom surface 16 of the top plate 13 to permit the tubular member to rotate freely. The tubular member extends downwardly to a point remote from the base plate leaving its bottom end free of the base plate. A platform in the form of an annular member or ring 20 is secured to the tubular member adjacent its lower end by means of a cross-piece 21 having a central opening 22 through which the tubular member extends. The tubular member and the platform may be made of the same material as the frame members. A number 10 of toy figures, such as dolls 23, are securely seated on the upper surface of the platform in any suitable manner.

The motor means for rotating the platform 20 includes an elastic member, such as an endless rubber band 24 which is disposed inside the tubular member 18 and which is detachably connected to bearing members 25. A bearing member 25 has a portion loosely mounted in and plugging the upper end of the tubular member 18, and another bearing member 25 is mounted with a forced fit in the bottom end of the tubular member in order to provide a rigid connection between said members.

The bearing members are substantially the same in construction and may be made of plastic, wood or other suitable material. Each bearing member comprises a cylindrical body 26 having an extension 27 of reduced diameter forming a shoulder 28 on the body. The extension is 15 formed with a transverse groove 29 in its outer surface at a point remote from the shoulder 28, said groove extending slightly more than 180 degrees around the extension. Grooves 30 are formed along opposite sides of the extension and 20 intersect the transverse groove 29. The grooves 30 extend from the transverse groove along the extension to the outer end thereof. The transverse groove extends laterally a slight distance beyond each groove 30 to form a notch 31 at each 25 side of the extension. The body portion 26 of the top bearing member 25 extends above the top plate 13 and is provided with a transverse opening 32 for receiving an elongated handle 33 which projects on both sides thereof for turning the 30 bearing member.

The rubber band 24 is in the form of an elongated endless loop and one end thereof is seated in the transverse groove 29 of the top bearing 25, and the other end is seated in the transverse groove 29 of the bottom bearing member, the reaches of the rubber band extending along and through the side grooves 30 of the bearing members. In assembling the bearing members and rubber band, the notches 31 permit the band to readily seat in the transverse and longitudinal grooves. 10

In use, either the tubular member 18 or platform 20 is held with one hand against movement while the handle 33 of the top bearing member is turned with the other hand in order to twist or wind up the rubber band 24. When the hand pressure is released, the rubber band unwinds and due to the rigid connection between the bottom bearing member 25 and the tubular member 18, said tubular member spins around 20 carrying its platform and toy figures around with it, as will be understood.

The shoulder 28 of the top bearing member 25 may be serrated as indicated at 34 to engage the roughened surface 17 of the enlarged portion 15 of the top plate 13 to prevent accidental turning of the top bearing member. 25

In the modification of the invention shown in Fig. 7, no frame structure is used. In this form, the tubular member 18 carries no platform but instead is provided with radially extending elongated handles 35 on opposite sides thereof, adjacent its bottom end. Also the handle 33 extending through the top bearing member 25 is made longer than the handle 33 of Fig. 1, and is formed with a peripheral groove 36 adjacent each end thereof. A toy figure, such as an airplane 37, is suspended from the handle, at each end thereof, by a flexible member 38 positioned in the adjacent groove 36. 30

In using this form of the invention, the top bearing member 25 is preferably held stationary with one hand, and the tubular member 18 rotated by the handles 35 so that the rubber band 24 is twisted and energized. When the hand pressure is released, the band will untwist and spin the top bearing member 25 with its toy figures around with it. Of course the rubber band could be twisted by holding the tubular member 18 stationary and by turning the top bearing member 25. Furthermore, the handles 35 could support suspended toy figures, if desired, in which case the tubular member 18 would be permitted to spin. 45

While I have illustrated and described the preferred embodiments of my invention, it is to be understood that I do not limit myself to the precise constructions herein disclosed and the right is reserved to all changes and modifications coming within the scope of the invention as defined in the appended claims. 50

Having thus described my invention, what I claim as new and desire to secure by United States Letters Patent is:

1. In a toy of the kind described, a frame in-

cluding a base plate, upright posts on the base plate and a top plate supported on top of said posts, a tubular member rotatably suspended from the top plate, a platform carried by said tubular member, a cylindrical bearing member loosely mounted in one end of said tubular member, another cylindrical bearing member closely fitted in the other end of said tubular member, an endless elongated looped rubber band having one end connected to said loosely mounted bearing member and having its other end connected to said other bearing member whereby turning of the loosely mounted bearing member twists the rubber band, and untwisting of said rubber band spins said tubular member, and toy figures on said platform.

2. In a toy of the kind described, a frame including a base plate, upright posts on the base plate and a top plate supported on top of said posts, a tubular member rotatably suspended from the top plate, a platform carried by said tubular member, a cylindrical bearing member loosely mounted in one end of said tubular member, another cylindrical bearing member closely fitted in the other end of said tubular member, said bearing members having transverse and longitudinal grooves, and an endless elongated looped rubber band having one end in the transverse and longitudinal grooves of the loosely fitted bearing member and having its other end in the transverse and longitudinal grooves of the closely fitted bearing member for twisting said rubber band, and toy figures on said platform. 20

3. In a toy of the kind described, a frame including a base plate, upright posts on the base plate and a top plate supported on top of said posts, a tubular member rotatably suspended from the top plate, a platform carried by said tubular member, a cylindrical bearing member loosely mounted in one end of said tubular member, another cylindrical bearing member closely fitted in the other end of said tubular member, an endless elongated looped rubber band having one end connected to said loosely mounted bearing member and having its other end connected to said other bearing member whereby turning of the loosely mounted bearing member twists the rubber band, and untwisting of said rubber band spins said tubular member, and toy figures on said platform, said top plate having a roughened surface and serrations on said first mentioned cylindrical bearing member adapted to engage said roughened surface to prevent accidental rotation. 40
